FIG. 4. Inventor:
Robert Garich,
By Lindsey Fletcher,
His Atty.

UNITED STATES PATENT OFFICE.

ROBERT GARICH, OF CHICAGO, ILLINOIS.

MASH-MACHINE.

SPECIFICATION forming part of Letters Patent No. 404,582, dated June 4, 1889.

Application filed January 23, 1889. Serial No. 297,317. (No model.)

To all whom it may concern:

Be it known that I, ROBERT GARICH, of Chicago, in the county of Cook and State of Illinois, have invented certain new and useful Improvements in Mash-Machines, of which the following is a full, clear, and exact description, reference being had to the accompanying drawings, forming a part of this specification, in which—

Figure 1 is a central vertical sectional view of a mash-machine embodying my improvements. Fig. 2 is a transverse sectional view of the shaft, taken upon the line $\alpha\alpha$, Fig. 1. Fig. 3 is a like view upon the line $\gamma\gamma$, Fig. 1; and Fig. 4 is a central vertical sectional view, in detail, of a portion of the machine, showing the parts in a reverse position from that shown in Fig. 1.

Like letters of reference in the different figures indicate like parts.

As is well known, in preparing the "mash" in the manufacture of beer the malt is placed in the tub and thoroughly agitated with hot water until the whole becomes a glutinous mass and the water becomes thoroughly impregnated with the sugar and other beer-making elements of the malt, when it is drawn off and used for making beer, while the "grains" or residue remain as a solid, heavy, pulpy mass, which it is necessary to remove before a new mash can be prepared in the tub. Machines have been constructed having revolving shovels or agitators and scrapers for removing this mass of residue from the tub by scraping and agitating it over an opening; but no means have been employed for raising and lowering the scrapers and shovels while in operation, or so that a portion only of the mass may be agitated at the beginning and the action upon the body increased until the whole is stirred up. Moreover, said residue is so heavy and solid after having become settled that the machinery heretofore used not only requires great expenditure of power to drive it, but is frequently broken in the attempt.

The object of my invention is to overcome this objection and to provide means for raising and lowering the entire agitating mechanism at will and while it is in operation, so that the power required to drive the machine may be lessened and the chances of breakage

diminished, while its efficiency is increased, all of which is hereinafter more particularly described and claimed.

Referring to the drawings, A represents an ordinary mash-tub having the usual false perforated bottom B, a secondary tight bottom C, valved pipe b, for removing the liquid from the mash, and an opening D for the removal of the grains. Mounted in a suitable bearing 55 e, supported in a frame-work at the top of the tub, and supported within a step e' at the bottom, is a vertical shaft E, which is driven by means of a gear e² at the top from any suitable source of power.

F is a sleeve loosely mounted upon the shaft E, but prevented from rotating thereon by means of a spline f. Rigidly attached to the sleeve F is a radial arm G, which is provided with rigid depending arms g g'. A shaft H 60 has one of its bearings in the lower end of the arm g, while the other is in a sleeve h', which is rigidly attached to the sleeve F. A secondary shaft J is rigidly attached to the arm g', and the sleeve j secured in like manner to the sleeve F. Rigid arms j', having scrapers j² j² upon their lower ends, are attached to the shaft J, so that when the sleeve F is lowered to its utmost extremity and rotated the scrapers j² are adapted to scrape the 65 false bottom B or to agitate the mash material at any point to which they may be raised. Upon the shaft H, I secure arms h², having shovels h³ thereon, which agitate the material 70 in the tub as the shaft H is rotated.

Extending through the bottom of the vat and attached thereto, or to any suitable framework or foundation, is a cylinder K, within which I place a loose piston K', through which the shaft E is extended. A pipe k is connected 75 with the bottom of the cylinder K and communicates with either a water or steam service pipe k' (whichever may be desired, but preferably the latter) and a waste or exhaust pipe k² by means of a two-way valve k³, by 80 which the water or steam may be directed into the cylinder K, as shown in Fig. 1, or allowed to escape therefrom, as in Fig. 4. Fitted loosely upon the outside of the cylinder K is a sliding sleeve L, Figs. 1 and 3, which is prevented from turning thereon by means of ribs 85 l₁, which fit into grooves formed in said sleeve,

as shown in Fig. 3. Preferably cast upon the top of the sleeve is a gear L' , into which meshes a gear h^4 , rigidly attached to the shaft H . Upon the admission of water to the cylinder K the piston K' is raised, and with it the sleeve L and the sleeve F , with the respective shafts and mechanism attached thereto. Upon turning the valve k^3 it may be lowered to any extent desired until the scrapers j^2 reach the bottom of the tub. Thus it is obvious that while the shaft E is being rotated all of the agitating and scraping mechanism may be in full operation and may be raised or lowered or retained at any desired elevation, which cannot be accomplished under the old constructions.

In lieu of the sleeve L and ribs l for preventing the gear L' from revolving, the piston k' may be bored to receive bolts $m\ m$, Fig. 4, which pass through the bottom cylinder-head and loosely into said bores. These may serve, also, to limit the downward movement of the piston. The upper end of the piston is provided with teeth $m'm'$, which are arranged to fit into corresponding notches in the gear L' .

Having thus described my invention, I claim—

1. In a mash-machine, the combination, with agitators arranged to rotate upon vertical and horizontal axes, respectively, of a single driving-shaft, a cylinder and piston in operative connection with said agitators and shaft, and means for lowering and raising said piston by hydraulic power, whereby said agitators may be positively and simultaneously rotated upon vertical and horizontal axes, respectively, and raised and lowered while in operation, substantially as shown and described.

2. In a mash-machine, the combination of a cylinder and piston, means for reciprocating said piston, a vertical shaft passing through the axis of said cylinder and piston, a non-rotating gear connected with said piston, a sliding sleeve splined to said shaft above said piston, a horizontal shaft radiating from said vertical shaft and having shovels thereon and a gear arranged to mesh into said non-rotating gear, a secondary radial shaft having scrapers depending from it, and means for driving said vertical shaft, substantially as shown and described.

3. The combination, in a mash-machine, of a vertical driving-shaft, a source of power, a sleeve loosely splined to said shaft, agitators, substantially as specified, attached to said sleeve, a cylinder and piston in operative connection with said sleeve, and means for actuating said cylinder, substantially as specified.

4. The combination, in a mash-machine, of a tub, vertical shaft E , a sleeve loosely splined thereon, arm G , having depending part g , horizontal shaft H , a hydraulic cylinder and piston, means for admitting water thereto, non-revolving gear L , in operative connection with said piston, and gear h^4 in engagement therewith.

In testimony whereof I have signed this specification, in the presence of two subscribing witnesses, this 3d day of January, 1889.

ROBERT GARICH.
